UNITED STATES PATENT OFFICE.

JACOB M. GOLDBERG, OF DENVER, COLORADO, ASSIGNOR TO THE COLORADO TENT & AWNING COMPANY, OF DENVER, COLORADO, A CORPORATION OF COLORADO.

CENTER-SUPPORT ASSEMBLY FOR TENTS.

Application filed March 27, 1926. Serial No. 97,954.

This invention relates to central supports for tents and has for an object to provide an assembly of center pole and associated parts in which there is combined the features of cheapness, simplicity in setting up for use, strength, rigidity and adjustability in use, lightness and compact collapsibility.

A further object is to provide an improved construction of center pole for tents.

With these and other objects in view the invention comprises certain novel constructions, combinations and arrangements of parts as will be hereinafter more fully described and claimed and as illustrated in

the accompanying drawing in which like characters of reference indicate corresponding parts throughout the several views and in which

Figure I is a view in elevation of the assembly set up in use.

Figure II is a longitudinal section of the same without the cap.

Figure III is a section of the cap.

Figure IV is a plan of the cap.

Figure V is a view of the pole sections telescoped completely.

This invention is intended primarily for use in tents for automobile campers and similar uses in which it is desirable that the equipment fold or collapse into a minimum of space and be of minimum weight while at the same time affording great supporting strength and simplicity in the matter of adjustment or arrangement for either use or packing for transportation. Cheapness is also a necessity in such a structure. The present invention combines said features and meets said requirements as will appear in the following description.

The main part of the assembly is a telescopeable, adjustable, supporting pole. The sections of this pole are made of thin tubing of metal having sufficient strength for the purpose and of such diameters respectively

that they will telescope one within the other. Any desired number of sections may be used but a three section pole has been found preferable for an ordinary automobile camping tent and has accordingly been shown in the drawing and will be described, it being understood that the number of sections may be changed without in any manner departing from the spirit of the invention.

One end section of the pole 1, may be a

plain piece of tubing as shown in Figures I 55 and II. An intermediate section 2 is of sufficient size to permit section 1 to telescope therewith and near one end is provided with indentations 3 forming seats on which the end of section 1 rests when inserted in 60 section 2 at the end nearest said indentations, as shown in Figures I and II.

The section forming the other end of the pole, indicated at 4 is of diameter to permit section 2 to telescope therewith and is 65 provided with indentations 5 similar to indentations 3 and forming a seat for the end of section 2.

To provide for stretching of the tent fabric, adjusting means are provided consisting of a series of holes 6 in section 4 and a pin 7. When it is desired to lengthen the pole to take up the stretched fabric, section 2 is raised off of seats 5 in section 4 and until the pole is thereby lengthened to the 75 desired extent and the pin 7 is inserted through a pair of the holes 6 and the end 8 of section 2 seats thereon, all as clearly illustrated at Figure II. It will be understood that while the holes 6 are shown as being in a vertical line, they may be arranged in a variety of orders and at such distances apart as the requirements of adjustment under various conditions of use may dictate.

When it is desired to pack the pole for transportation, the sections are separated and section 2 is inserted into the end of section 4 farthest from seats 5 and the relative lengths of the sections and the relative positions of the seats therein are preferably such that the distance from seats 5 to the farthest end of section 4 will equal the length of section 2 whereby section 2 may be completely inserted therein.

It will be noted that there are no projections on the outside of the sections, whereby section 2 may be completely inserted in section 4 as above stated.

When section 1 is telescoped within section 2, the end section 1 may, and in practice commonly does, project a little beyond the end of section 2. In such case when section 2, carrying section 1 telescoped therewith, is inserted within section 4, the end of section 1, projecting beyond section 2, 105 may encounter seats 5 and thus cause section 2 to project a little beyond the end of section 4. In common practice this slight pro-

jection has not been found objectionable but when complete telescoping of section 2 within section 4 is desired it is accomplished by having the indentations 5 project inwardly 5 from the inner wall of section 4 a distance not exceeding the thickness of the wall of section 2 so that the cross section area of section 4 between the seats 5 will slightly exceed the cross section area of section 1 so 10 that section 1 may project between seats 5 and both sections 1 and 2 entirely telescope within section 4 all as clearly shown at Fig. V.

Because the lower end or base of section 15 4 is open and would, therefore, tend to damage the canvas floor of the tent where such floor is used, or sink into the ground when there is no artificial flooring, a base plate 9 is provided of sufficient size to afford a suitable footing or base to support the pole. This plate is of rigid construction, this being accomplished preferably by providing a ring 10 with the edge of the plate rolled over the ring 10 as clearly shown at Figure II. 20 25 Centrally of the plate 9 there is preferably provided a depression 11 forming a seat for the base of the pole as clearly shown at Figure II.

When this assembly is to be used in a 30 tent having a canvas floor, the plate is preferably attached to the canvas floor at the center thereof by suitable means as by rivets.

12. When thus attached the seat 11 is in the center of the tent and thus the center-

ing of the base of the pole is assured by 35 setting the pole in seat 11.

To protect the canvas at the peak of the tent, while leaving the peak entirely closed, and to provide a suitable seat for the upper end of the pole within such closed peak, 40 cap 13 of rigid construction, preferably stamped out of thin steel, is provided and is attached to the tent cloth by any suitable means as by sewing through holes 14. A suitable seat 15 is provided in the cap for 45 the end of the pole.

The operations of setting up the pole for use and taking it down and packing for transportation will be obvious from the foregoing description and the drawing. 50

I claim:

1. A tent supporting structure comprising a pole of tubing having open ends, a rigid cap in the form of a hollow truncated cone for forming a seat for the top of the pole 55 in the peak of the tent and a base plate for said pole having a seat therein for the base of the pole and a rolled edge for making said plate rigid.

2. A tent supporting structure comprising, in combination, an open ended tubular pole, a metal cap carried by the tent in its peak and having a pole seat therein and a thin rigid base plate carried by the floor of the tent at a point directly beneath said cap 60 and having a pole seat therein. 65

In testimony whereof I affix my signature.

JACOB M. GOLDBERG.
